DESIGN FOR AN AIRPLANE

William J. Clark, Bexley, Ohio, assignor to Curtiss-Wright Corporation, a corporation of Delaware

Application March 17, 1947, Serial No. 137,673

Term of patent 14 years

(Cl. D71—1)

To all whom it may concern:

Be it known that I, William J. Clark, a citizen of the United States residing in Bexley, in the county of Franklin and State of Ohio, have invented a new, original, and ornamental Design for Airplanes, of which the following is a specification, reference being had to the accompanying drawing, forming a part thereof.

Figure 1 is a side perspective view;

Figure 2 is a plan view;

Figure 3 is a side elevational view; and

Figure 4 is a front elevational view of an airplane, showing my design.

I claim:

The ornamental design for an airplane, as shown.

WILLIAM J. CLARK.
